UNITED STATES PATENT OFFICE

152,130

DESIGN FOR A COMBINED CRIB AND BUREAU

Johannes Staartjes, Amsterdam, Netherlands, as-
signor to Bruynzeel's Deurenfabriek N. V.,
Zaandam, Netherlands

Application January 22, 1946, Serial No. 125,845
In the Netherlands July 19, 1945

Term of patent 14 years

(Cl. D5—5)

To all whom it may concern:

Be it known that I, Johannes Staartjes, a Dutch subject, residing at Amsterdam, Holland, have invented a new, original, and ornamental Design for Combined Crib and Bureau, of which the following is a specification; reference being had to the accompanying drawings, forming part thereof.

Figure 1 is a perspective view of one side and end of the combined crib and bureau of my new design, and

Fig. 2 is a perspective view of the other side and other end of the combined crib and bureau.

I claim:

The ornamental design for a combined crib and bureau, as shown.

JOHANNES STAARTJES.
